UNITED STATES PATENT OFFICE

CHARLES M. MARKHAM, OF TOLEDO, OHIO

SHORE ATTACHMENT

Application filed October 14, 1929. Serial No. 399,484.

This invention relates to a shore attachment particularly adapted to be used in concrete construction work for securing forms for concrete joists or girders at the upper ends of the shores.

The general object of the invention is to provide a device which may be easily and quickly applied to the upper end of a shore beam and adjusted to hold the walls of the concrete form firmly in position without the use of braces or other holding means except those embodied in the device itself. The device may be used over and over again on successive jobs with a great saving in the cost of labor and material.

The invention will be more particularly described in connection with the accompanying drawings, in which

Figure 1 is a side elevation of the improved attachment, showing in section the form held thereby.

Figure 2 is a section taken on the line 2—2 of Figure 1.

Figure 3 is a section taken on the line 3—3 of Figure 1.

Figure 4 is a section taken on the line 4—4 of Figure 1.

As illustrated in the drawings, my invention is mounted on the upper end of a post or shore beam 5. The head which is thus supported comprises a steel beam 6, which is T-shaped in cross section, with the middle portion of the flange 7 cut away to receive the end of the shore beam 5.

The attachment also includes two opposed channel bars 8 embracing opposite faces of the shore beam at its upper end. The ends of the channel bars 8 are connected on each side by strips 9, and the lower ends of the channel bars 8 are connected by diagonal braces 10 in the form of channel bars to the end portions of flanges 7. The parts 6, 7, 8, 9 and 10 are all welded or otherwise permanently secured together to form a strong and rigidly constructed head for supporting the concrete form which is shown as having a bottom 11 and side walls 12.

The form is adapted to be held between two clamping members which are mounted on the T-beam 6. Each of these clamping members

is in the shape of a right triangle having a vertical side 13 adapted to abut the face of the side wall 12. An integral brace 14 constitutes the hypotenuse of the triangle and the base is formed with clips 15 and 16 slidably engaging the side flanges of the beam 6 and rigidly connected by a tie rod or bar 17.

For adjusting these clamping members to clamp the form tightly, the T-beam 6 is formed with series of slots 18 selectively engageable by wedges 19. The slots 18 are arranged in staggered relation so that for any position of the side wall 12 the wedge may always be driven into one of these slots to force the clamping member against the face of the form. Each wedge 19 may be conveniently carried on the end of a chain 20 which is connected with the diagonal brace 14.

From the foregoing description it will be seen that after the shore beam is placed in position with my improved attachment on its upper end and the concrete form resting thereon, the clamping members may be quickly secured in clamping position by driving the wedges 19 into the proper slots. After the concrete has set the shore may be just as readily removed by knocking out the wedges 19 and may be immediately used on another job. It will be appreciated that the same shores and clamps may be used over and over again and that the expense for labor and material is very greatly reduced thereby.

While I have shown and described specifically the preferred form of the invention, it will be understood that the same is capable of various modifications and other uses which fall within the scope of the appended claim.

What I claim is:

A shore head comprising a casing adapted to fit over the upper end of a shore beam, a T-beam constituting a cross head adapted to rest horizontally upon the end of the shore beam, opposed clamping members in the form of right triangles having bases formed with clips engaging about the side flanges of the T-beam to hold the clamping members with their perpendicular legs presenting opposed parallel abutments, said T-beam having series of longitudinally disposed slots in its side flanges arranged in staggered relation on op-

posite sides of its vertical web and adjacent thereto, and wedges selectively insertable in said slots to force said clamping members progressively toward each other to clamp a

5 form between them.

In testimony whereof I have hereunto signed my name to this specification.

CHARLES M. MARKHAM.
